COMBINED CLOCK AND WALL PLAQUE

John H. Jordan, Jr., 8124 S. Crandon Ave.,
Chicago, Ill. 60617

Filed Aug. 4, 1970, Ser. No. 24,293

Term of patent 14 years

Int. Cl. D10—01

U.S. Cl. D42—7

FIG. 1.

FIG. 2.

FIG. 3.

FIG. 4.

FIG. 5.

FIG. 1 is a top plan view of a combined clock and wall plaque showing my new design;

FIG. 2 is a side elevation thereof;

FIG. 3 is a front elevation;

FIG. 4 is a sectional view taken on line 4—4 of FIG. 3, and looking in the direction of the arrows; and

FIG. 5 is a rear elevation.

I claim:

The ornamental design for a combined clock and wall plaque, as shown.
